RESONATOR

Benedict Cassen, Pittsburgh, Pa., assignor to Westinghouse Electric Corporation, East Pittsburgh, Pa., a corporation of Pennsylvania

Original application April 19, 1941, Serial No. 389,351. Divided and this application February 12, 1942, Serial No. 430,601

3 Claims. (Cl. 178—44)

My invention relates to electric discharge apparatus and has particular relation to high voltage discharge tubes, such as generators of hard X-rays.

This application is a division of my copending application Serial No. 389,351, filed April 19, 1941, now Patent No. 2,342,789, Feb. 29, 1944, and assigned to the Westinghouse Electric & Manufacturing Company.

In producing X-rays having a wave length less than .25 Angstrom, a potential greater than 50,000 volts is impressed between the cathode and the anode. If the potential is impressed directly from an alternating current source or from a battery of accumulators, the usual high voltage problems arise. Either the cathode or the anode is at a high potential relative to ground and elaborate insulation is required to prevent arcing between the parts of the system in electrical contact with or adjacent to either of the two electrodes. The cooling coils, which are essential for such high power apparatus, present a particularly serious problem in this respect. Protective equipment of elaborate design is also required to assure that operators, people who are being treated with the apparatus and others in the vicinity of the apparatus are not injured by the high potentials.

It is, accordingly, an object of my invention to provide a generator of hard X-rays having a wave length less than .25 Angstrom which shall incorporate no high voltage insulating and protective equipment.

A more general object of my invention is to provide a high voltage electric discharge device which shall incorporate no insulating and protective equipment for high voltages.

Another general object of my invention is to provide an efficient high voltage electric discharge device.

A more specific object of my invention is to provide apparatus for radiating X-rays in precisely timed discrete pulses.

An ancillary object of my invention is to provide a circuit for coupling an oscillation generator to a hollow body resonator in such manner that the generator locks into stable oscillation with the resonator.

Another ancillary object of my invention is to provide an efficient hollow body resonator.

More concisely stated, it is an object of my invention to provide an efficient high voltage X-ray system that shall not incorporate the insulating equipment ordinarily required for the high voltage involved.

My invention arises from the realization that the high voltage necessary to produce hard X-rays may be impressed as the electric component of a high frequency electromagnetic field entirely within a hollow body resonator. Externally such a resonator is throughout at ground potential, and, therefore, neither the cooling system nor the other parts of the apparatus need be elaborately insulated in spite of the high potential impressed within the resonator.

In accordance with my invention, I provide a discharge device comprising a hollow body resonator within which an electron emitter is disposed. The resonator is coupled to a suitable oscillation generator which produces an electromagnetic field within the resonator and under the action of the field electrons flow from the source through the resonator. An X-ray target is disposed in the path of the electrons, and as the electrons impinge thereon, X-rays of the desired wave length are produced.

In accordance with the broader aspects of my invention, the resonator may be an ordinary hollow tank, the internal surface of which is conductive. When such a tank is excited to oscillate, a standing electromagnetic wave or fractions of a wave is produced along a dimension of the tank corresponding to the mode of oscillation and the electrons from the emitters flow through the tank along a path determined by the electric component of the field of the wave. The wave has potential nodes at conductive walls of the tank which are transverse to the dimension of oscillator and voltage loops intermediate the nodes. Hereinafter, I shall refer to the potential produced by the electromagnetic field as the electromagnetic potential to distinguish it from the usual direct or low frequency alternating potentials which may be used in the apparatus. The electron flow is produced by a field which arises from the difference of electromagnetic potential between the emitter and the points in the resonator which are at any instant at a higher electromagnetic potential than the emitter. The emitter should be so disposed in the tank that the electrons in passing through the tank are subject to the potential of the field for an interval of time that is short compared to a period of the field. If the electron path is so long that the electrons are effected by the field during an interval of time of the order of a period of the field, the electrons are both accelerated and decelerated while traversing their path and do not have the necessary energy when they impinge on the target.

Conveniently my invention may be practiced in its broad aspects with a resonator in the form of a completely closed hollow cylinder. In the principal mode of oscillation of such a cylinder the resonant electric field is in an axial direction and has a wave length approximately equal to twice the diameter. Conducting leads carrying an electron emissive filament are sealed through one base of the cylinder and a target is supported from the opposite base. The height of the cylinder or the length of the filament leads should be such that the path over which the electrons are accelerated by the field is short compared to a quarter wave length of the resonant field. When the cylindrical resonator is excited to oscillate the potential wave has a node at the circumference of the cylinder and a loop on the axis; the potential difference within the cylinder is axial. The maximum potential difference at any instant is impressed between the bases along the axis. Current flows between the emitter and the target under the action of the axial potential difference. The return path of the current is along the wall of the cylinder, along the base through which the emitter is sealed and along the emitter leads.

The resonator is excited to oscillate from a suitable oscillation generator coupled to the resonator. In the practice of my invention I have found that the cylindrical resonator is bulky if it is designed to have a resonance wave length at which sufficient power for X-ray purposes is available.

This situation may be remedied by providing in lieu of the cylindrical resonator, a resonator made up of a cylindrical shell with a reentrant cylindrical protuberance through which the emitter projects. The height of the protuberance is such that its upper terminal is disposed adjacent to the opposite base of the resonator. The emitter extends just through the end of the protuberance adjacent the resonator base and the target is mounted within the base. Such a resonator has a principal resonant wave length approximately equal to four times the height of the shell. The lines of force of the electric field produced when the resonator is excited to oscillate extend radially between points on the protuberance and corresponding points on the shell. The distance between the protuberance and the opposite base of the resonator is such that the time during which the electrons are subject to the field between the emitter and the base is short compared to a quarter period of the resonance frequency. When the resonator is excited to oscillate, a wave having a potential node in the region where the protuberance joins the shell and a loop near the opposite base of the shell is produced. In this case the return path for the current which flows between the emitter and the target is along the internal surface of the outer cylinder, along the surface joining the outer cylinder and the protuberance, and along the internal surface of the protuberance. In addition to the discharge current there is a large high frequency resonant current which is greatest along the joining surface and tends to concentrate at the junction of the protuberance and the surface.

To minimize power loss, it is desirable that the area bounded by the curve which is defined by the junction (the diameter of a circle of the protuberance is a circular cylinder as is usual) be as large as is practicable. This desideration can not be achieved simply by providing a protuberance having bases of large area because as small

an area as is practicable is desirable at the internal end of the protuberance. The magnitude of the electromagnetic voltage produced is dependent on the characteristic impedance of the resonator in the region of the voltage loop. The latter impedance is the greater, the greater the ratio of the area of the base of the outer shell to that of the protuberance in the region of the loop. Where the shell and the protuberance are of circular cross section the characteristic impedance is proportional to the logarithm of the ratio of the diameter of the outer shell to the diameter of the protuberance in the region of the loop. For a given shell diameter, the ratio and, therefore, the electromagnetic voltage, is a maximum if the protuberance diameter at the internal end is a minimum.

The conditions for minimum power loss and maximum electromagnetic voltage may both be satisfied by providing a resonator having a reentrant conical protuberance. The protuberance is preferably of circular cross section and tapers from a large diameter base at one base of the shell substantially to a point near the other base of the shell. The junction curve between the protuberance and the former base of the outer shell is a circle of large diameter, and the losses at the junction are minimized. The ratio of the diameter of the shell near its other base to the diameter of a point is high and therefore the electromagnetic voltage is large for the dimensions involved.

The ratio which governs the characteristic impedance is a maximum if the shell is cylindrical. However, a conical shell with a conical protuberance is less cumbersome and weighs less than a cylindrical shell with a conical protuberance. Since for resonators most frequently encountered in practice, the characteristic impedance ratios are not appreciably different for the two structures, I prefer to use a conical resonator with a reentrant conical protuberance in the practice of my invention. My invention is not, of course, limited to this preferred practice.

In accordance with the broader aspects of my invention, the resonator may have any desired dimensions. However, from a practical standpoint I have found that certain dimensions are to be preferred.

The resonant wave length of a conical (or cylindrical) resonator having a reentrant protuberance is roughly four times the distance between the bases of the outer shell. Since X-rays are produced in a high vacuum the resonator is highly evacuated and to minimize vacuum problems, it is desirable that the resonator be small. Aside from physical limitations, the exiguity of the dimensions of the resonator is limited by the practical consideration that oscillators for exciting a resonator sufficiently to produce X-rays are not available at small wave lengths. I have found that an oscillator capable of supplying more than 200 watts steady power and 10 to 50 kilowatts in discrete pulses is necessary for X-ray purposes. Such an oscillator is conveniently available only at wave lengths greater than two meters. To avoid vacuum difficulties, the resonance wave length of the resonator should not be greater than 12 meters. In accordance with a specific aspect of my invention, the resonant wave length of the resonator should lie between 2 and 12 meters and should preferably be of the order of 4 meters.

The oscillator which is used in the practice of my invention to excite the resonator comprises

electric discharge valve means, the output circuit of which is connected through a coupling loop to the resonator. The resonator is a massive structure, and its dimensions cannot conveniently be varied for tuning purposes. A problem, therefore, arises in adjusting the oscillator to lock into stable oscillation with the resonator. In accordance with a still further aspect of my invention, the impedance between the loop and the output electrodes of the discharge valve means is varied until the oscillator and the resonator lock into stable oscillation. I have found that stability is attainable over a substantial range of the impedance and precise adjustment to a critical point is not essential.

It is desirable that the flow of electrons from the emitter to the target be limited to the time intervals during which the electromagnetic potential tending to draw electrons from the emitter is high. If electrons flow from the emitter during the intervals when the potential is relatively low, they, to a large extent, fail to reach the target and to circulate in the resonator causing excessive loss. To limit the flow of electrons in the high potential intervals, the emitter is shielded by a screen conductively connected to the resonator and a biasing potential of several hundred volts is interposed between the emitter and the resonator. The potential prevents the electrons from penetrating the screen into electromagnetic field and the target, unless the potential produced by the field is of large magnitude.

The novel features that I consider characteristic of my invention are set forth with particularity in the appended claims. My invention itself, however, both as to its organization and its method of operation, together with additional objects and advantages thereof, will best be understood from the following description of specific embodiments when read in connection with the accompanying drawing, in which:

Figure 1 is a diagrammatic view showing an embodiment of my invention; and

Fig. 2 is a graph illustrating the operation of my invention.

The apparatus shown in Fig. 1 comprises a hollow body resonator 3 made up of an external conical shell 5 and a reentrant conical protuberance 7. The protuberance 7 tapers in the same direction as the shell 5 and is preferably coaxial with the shell. In accordance with the broader aspects of my invention, the protuberance and the shell need not be coaxial, but their axes should preferably be parallel. The distance between the small diameter base 9 of the protuberance 7 and the small diameter base 11 of the shell 5 is short compared to the height of the shell. The ratio between the shell height and the distance between the small diameter bases should be of the order of 5:1 to 10:1. Cooling coils 13 are provided about the surface 15 joining the large diameter ends of the protuberance and the shell.

The shell 5, the protuberance 7 and their joining surface 15 of the embodiment shown in Fig. 1 are composed of an electrically conductive material such as copper. In accordance with the broader aspects of my invention, the resonator need not be composed of conductive material but it is essential that the inner surface of the resonator be conductive.

A central opening 17 is provided in the base 11 of the shell 5. Over the opening a closed cylindrical tube 19 having a flat cover 21 at an angle of approximately 45° to the axis of the tube is secured. The tube 19 is preferably com-

posed of Monel metal, and the cover 21 has a thickness of the order of one-tenth of an inch. The inner surface of the top is faced with lead 23 or any other high-atomic-weight material. The tube is provided with ears 25 and is held tightly against a gasket 27 disposed over the opening 17 in the shell 5 by bolts 29 which pass through the ears and engage the small base 11 of the shell. A suitable water-cooling jacket 31 is provided about the tube 19 and its top 21.

The small diameter base 9 of the protuberance 7 is rounded off so that it, in effect, constitutes a point rather than a surface of extensive area. It is provided with an opening 32 through which an electronic emitter assembly 33 extends. The assembly comprises a ring shaped filament 35 of tungsten or any other suitably emissive material 37. A pair of rigid conducting leads 39 are welded to the filament 35. The leads and the filament are enclosed within a narrow electrically conductive cylinder 41 open at the end remote from the filament 37. The open end is sealed vacuum-tight by an insulating plug 43 preferably composed of glass and the leads 39 are sealed vacuum-tight through the plug 43. The leads are of such length that the filament is adjacent the unsealed end of the tube 41. The end 45 of the tube 41 near the filament is closed but has a central opening 47 of small diameter. Insulating spacers 49 are provided within the tube 41 to prevent the leads 39 from contacting the tube. The tube extends a short distance through the small diameter base 9 of the protuberance 7 and is hard-soldered vacuum-tight to the protuberance by a solder ring 51 melted at the junction between the protuberance and the tube.

The tube 41 is thus conductively connected to the resonator 3 but the filament 37 is insulated from the resonator. The perforated end 45 of the tube 41, in effect, constitutes a screen about the filament 37 and the flow of electrons from the filament may be controlled by controlling the potential between the end 45 (i. e., the resonator) and the filament.

The resonator 3 is supported from hollow tubular arms 53 and 55 extending from diametral openings near the large diameter end of the outer shell 5 in a direction perpendicular to the axis of the shell. The arms are soldered vacuum-tight to the outer shell. A sleeve 57 is secured to each of the arms and the sleeves are rotatably supported on ball-bearing wreaths 59 which are suspended from a fixed supporting bracket 61. The resonator 3 may thus be rotated about an axis determined by the arms 53 and 55.

One of the arms 53 communicates with a pump system 63 through a Sylphon 65. The system comprises a tubular oil-diffusion pump 67, the suction tube 69 of which is secured vacuum-tight to the Sylphon 65 and a mechanical pump 71 having its suction tube 73 connected to absorb gas from the tubular diffusion pump. Sleeves 75 are secured about the wall of the diffusion pump near its oil reservoir 77 and near its suction opening. The sleeves 75 are rotatably supported on ball bearing wreaths 79 suspended from a rigid bracket 81. The diffusion pump 67 may thus rotate with the resonator 3. The tube 83 from the suction opening 73 of the mechanical pump 71 is sufficiently long and flexible to permit free rotation of the diffusion cylinder 67 and the resonator 3, and the Sylphon 65 takes up any difference in displacement between the diffusion pump and the resonator arising from the rotation.

The remaining tubular supporting arm 55 is

sealed vacuum-tight by a plug 85 of insulating material, such as glass. A coupling loop 87 extending from terminals 89 sealed through the plug 85 projects into the space between the protuberance 7 and the shell 5 adjacent the supporting arm 53. The loop 87 should be so positioned as to be threaded by a portion of the flux of the magnetic component of the field produced within the resonator 3 when the latter is excited. When the resonator 3 is rotated, the position of the loop relative to the resonator field should not change, and, therefore, the loop should be rotated with the resonator. To provide for the free rotation of the loop while the parts to which it is connected externally are fixed, the terminals 89 of the loop are connected to movable brushes 91 which engage fixed conductive rings 93.

The resonator 3 is excited from a high frequency oscillation generator 95. The generator comprises a pair of three-electrode high-vacuum discharge tubes 97 and 99, each having an anode 101, a cathode 103, and a control electrode 105. The control electrodes are connected together by a short conductor 107. To the center 109 of the conductor or terminal, a biasing network consisting of a resistor 111 and a capacitor 113 in parallel is connected. The other terminal of the network is connected to a conductor 115 which connects the cathodes 103.

From each of the anodes 101 of the discharge devices 97 and 99 rigid conductor 117 extends. Each of the conductors engages a ring 93 to which the loop terminals 89 are connected. The anode conductors 117 are bridged by a conducting bar 119, the position of which along the conductors may be adjusted.

The bridging bar 119 is connected to a grounded line conductor 121 of an alternating current source (not shown). The other line conductor 123 of the source is connected to the conductor 115 which connects the cathodes. The oscillator 95 may be enclosed within a shielding container 125 provided with a neck 127 within which the rings 93 connected to the loop 87 are mounted. The resonator 3 is grounded but the loop 87 and its terminals 89 are insulated from the resonator.

The anode conductors 117, the loop terminals 89, the loop 87 and the bridging conductor 119 constitute the output circuit of the oscillator 95. The character of the interaction of the oscillator and the resonator 3 may be determined by adjusting the position of the bridging bar 119 along the anode conductors 117. The bridging bar may be so disposed that the portions of the anode conductors between the bar and the anodes 101 are shorter than that required for stable oscillation of the generator 95 and the resonator 3 as a unit. This situation arises when the anode conductors and the bridging bar have a low impedance compared to the equivalent impedance of the loop 87 and the resonator 3, and in such an event the oscillator operates independently of the resonator. The bridging bar 119 may be so positioned that the portion of the anode conductors between the bar and the anodes are too long. The resistance of the anode conductors and the bridging bar is then so high that no oscillations are produced by the generator 95. Intermediate these extreme positions of the bridging bar 119 there is an extended region for which the resonator 3 and the oscillator 95 lock into stable oscillation. In other words, because the index of electrical efficiency "Q" is so high for the hollow resonator, there is a finite range of positions of the bar 119 in which the frequency of

the oscillations produced by the generator 95 is controlled by the dimensions of the resonator and not by the position of bar 119. Over this range, the shorting bar 119 may be positioned to act as a means of supplying the necessary inductance for the oscillator 95 to lock into for efficient power transfer.

When the resonator is properly excited by the oscillator 95, an electromagnetic field the electric component of which is radial is produced within the resonator and a difference of electromagnetic potential exists between points along the protuberance and points along the shell radially displaced from the protuberance points. Between the apex 9 of the protuberance and the opposite base of the shell the lines of force of the electric component of the electromagnetic field extend at gradually decreasing angles to the axis of resonator as the axis is approached and they are along the axis between the center of the apex and the center of the base 11. An electromagnetic potential difference is therefore impressed between a point just outside of the screen 45 and a central point near the base 11 of the shell 5 opposite the filament.

The standing electromagnetic potential wave which is produced along the resonator 3 is illustrated graphically at any instant in Fig. 2. Distance is plotted vertically and potential horizontally towards the right. To illustrate how the potential varies along the resonator, the outline of the resonator is shown in broken lines. The full-line quarter-sine V_r represents the electromagnetic potential difference between corresponding radial points along the protuberance 7 and shell 5. For example the potential difference between point P_p on the protuberance and point P_s on the shell is given by the potential coordinate of the point V_p . The potential difference between the screen 45 and the base 11 is given by the maximum voltage coordinate of the curve V_r (at the point L).

The potential wave has a node N at the large diameter end of the resonator and a loop L near the small diameter base 11 of the shell. A current loop coincides with the potential node N and the current is, therefore, large along the large diameter surface 15 of the resonator. It is for this reason that the surface is provided with cooling coils 13.

The potentials along the resonator 3 represented by the curve V_r is an alternating potential having a high frequency determined by the resonator 3; the corresponding wave length being approximately four times the length of the resonator. Since the anode-cathode potential impressed on the tubes 97 and 99 of the generator which excites the resonator is of the alternating type, the electromagnetic potential within the resonator is modulated at the frequency of the alternating current potential impressed on the tubes. The alternating current potential frequency is small compared to the resonant frequency of the resonator.

A potential 128 is interposed between the filament 35 and the resonator 3 maintaining the direct current potential of the resonator negative relative to that of the filament. The potential functions as a negative bias between the perforated cover 45 of the tube 41 which encloses the filament and the leads 39 and controls the flow of electrons from the filament to the small diameter base of the shell.

Electrons flow from the filament 35 under the combined action of the biasing potential 128 and

the modulated electromagnetic potential. The electron flow from the filament is blocked by the biasing potential until the electromagnetic potential exceeds a predetermined magnitude. At this point the electrons are drawn from the field of the screen 45 into the high electromagnetic field between the screen and the small diameter base 11 of the shell 5. In the latter region, they are accelerated and pass through the opening 17 in the small diameter base into the tube 19. The space within the tube is field free and the electrons pass through the tube and impinge on the target 23 producing X-rays. The electromagnetic potential difference to which the electrons are subject is so high that X-rays having a wavelength less than .25 Angstrom are produced. The radiation is in discrete pulses having a periodicity and amplitude determined by the modulating frequency and amplitude and the biasing potential.

In a system constructed in accordance with my invention, the length of the resonator 3 is 48 inches. The largest diameter of the outer shell 5 is 32 inches. The smallest diameter of the outer shell is 14 inches. The distance between the small diameter base 11 of the outer shell and the small diameter base 9 of the protuberance 7 is 9 inches. The large diameter of the protuberance is 18 inches. Its small base is a rounded-off surface originally 4 inches in diameter. The discharge devices 97 and 99 used in the oscillation generator 95 in an embodiment of my invention are Westinghouse WL-889 tubes. The anode-cathode potential impressed on each of the devices is an ordinary commercial 60-cycle potential having a peak magnitude of 12,000 volts. The resistor 111 in the biasing network is 5,000 ohms, and the capacitor in the network is the distributed capacity of the resistor.

Although I have shown and described certain specific embodiments of my invention, I am fully aware that many modifications thereof are possible. My invention, therefore, is not to be restricted except in so far as is necessitated by the prior art and by the spirit of the appended claims.

I claim as my invention:

1. A hollow body resonator comprising a hollow conical enclosure having a re-entrant conical protuberance with the axis of said protuberance substantially parallel to the axis of said enclosure, said conical protuberance tapering in the same direction as said conical enclosure, the internal surface of said enclosure including said protuberance being electrically conductive.
- 10 2. A hollow body resonator comprising a hollow conical enclosure having a re-entrant conical protuberance, said enclosure and protuberance being coaxial and tapering in the same direction, the internal surface of said enclosure including said protuberance being electrically conductive.
- 15 3. A hollow body resonator comprising a hollow enclosure having a re-entrant conical protuberance with the axis of said protuberance extending in substantially the same direction as the axis of said enclosure, said enclosure and protuberance being tapered in the same direction, said protuberance and the remainder of said enclosure bounding an annular space between their side walls and a conical space of substantially smaller height than the height of said enclosure between their ends, the internal surface of said enclosure including said protuberance being electrically conductive.

BENEDICT CASSEN.
